PENICILLIN SALTS OF N-METHYL-(2-HYDROXY-1,2-DIPHENYLETHYL)-AMINE

Vernon V. Young, Terre Haute, Ind., assignor to
Commercial Solvents Corporation, Terre Haute,
Ind., a corporation of MarylandNo Drawing. Application January 22, 1952,
Serial No. 267,695

7 Claims. (Cl. 260—239.1)

1

This invention relates to salts of penicillin and more particularly it relates to penicillin salts of N-methyl-(2-hydroxy-1,2-diphenylethyl) amine.

All penicillin salts are not practical for therapeutic use. For example, a penicillin salt may not be stable at ordinary temperatures and thus in order for the therapeutic activity of the salt to be retained, it must be refrigerated during storage or else rapid deterioration of the therapeutic activity occurs. Some penicillin salts are too toxic for use therapeutically and hence must be ruled out completely.

In addition to the stability and toxicity characteristics of penicillin salts, consideration must also be given to their solubility properties. The expression of favorable solubility properties is found in the measurement of blood levels of penicillin at intervals after injection into or ingestion by the body. The longer penicillin can be found in the blood after it has been placed in the body, the more effective it is against the pathogenic organisms present in the body, provided they are penicillin susceptible. If, however, blood levels of penicillin are only maintained for short periods after injection or ingestion of the penicillin salt, the penicillin content of the salt is largely wasted and there is little or no alleviation of the pathological condition being treated unless there are repeated administrations of the penicillin salt at short intervals.

Furthermore, it has been found that about 10 per cent of all patients treated with most previously known penicillin compounds are allergic to the drug and upon administration thereof serious complications in the form of "hives" often occur. Treatment is, therefore, denied a great many people because of their allergy.

An object of the present invention is to provide stable penicillin salt compositions of low toxicity which give prolonged blood levels of penicillin whether given orally or by injection, and which are non-allergic to persons presently denied the drug for this reason.

I have now discovered stable penicillin salts possessing low toxicity characteristics which give prolonged blood levels after being injected into the body or after being administered orally and which have pronounced anti-allergic properties thus making penicillin available to a great many more people. My new compositions are penicillin salts of N-methyl-(2-hydroxy-1,2-diphenylethyl) amine.

N-methyl-(2-hydroxy-1,2-diphenylethyl) amine contains two asymmetric carbon atoms and thus two racemic modifications and four optically active isomers are possible. The penicillin salt of

2

the levo isomer of the erythro pair of N-methyl-(2-hydroxy-1,2-diphenylethyl) amine can be prepared by mixing one equivalent of a water soluble penicillin salt such as potassium penicillin G in aqueous solution with two equivalents of an aqueous solution of the hydrochloride of dl-N-methyl-(2-hydroxy-1,2-diphenylethyl) amine obtained by the reductive amination of benzoin with monomethylamine. The crystalline penicillin salt of 1-N-methyl-(2-hydroxy-1,2-diphenylethyl) amine precipitates from the aqueous solution and is recovered therefrom by filtration and dried. (Nitrogen analysis: calculated 7.48%; found 7.38%. Carbon analysis: calculated 66.28%; found 66.33%. Hydrogen analysis: calculated 6.28%; found 6.18%. Melting point 186-191° C. with decomposition. Specific rotation in 50% acetone-water at 25° C. taken within one-half hour after dilution is +124° ± 5°.) The dextro isomer of the same pair does not form a salt with penicillin under the above conditions but the unreacted isomer can be recovered from the filtrate by adjusting the pH between 9-10 with an aqueous solution of sodium hydroxide. One mole of potassium penicillin is reacted with two moles of dl-N-methyl-(2-hydroxy-1,2-diphenylethyl) amine in order to obtain near quantitative yields of the salt of the levo isomer based on the quantity of penicillin used due to the presence of the dextro isomer.

The penicillin salt of the dextro isomer can be prepared by reacting it with an equivalent amount of free benzyl-penicillanic acid in an organic solvent such as ethyl ether or butyl acetate. Crystallization can be induced by seeding or scratching. (Nitrogen analysis: calculated 7.48%; found 7.33%. Carbon analysis: calculated 66.28%; found 66.21%. Hydrogen analysis: calculated 6.28%; found 6.18%. Melting point 148-151° C. with decomposition. Specific rotation in 50% acetone-water at 25° C. taken within one-half hour after dilution is +220° ± 5°.) The terms dextro and levo or d and l as used in this specification and the attached claims refer to the dextro and levo isomers of the erythro pair of N-methyl-(2-hydroxy-1,2-diphenylethyl) amine. The l and d-N-methyl-(2-hydroxy-1,2-diphenylethyl) amine salts of other forms of penicillin such as penicillin F, penicillin K, etc. can be prepared in the same manner as described above for penicillin G.

The levo and dextro isomers forming the threo racemate of N-methyl-(2-hydroxy-1,2-diphenylethyl) amine are prepared by inverting the dextro and levo isomers of the erythro pair using the method of Welsh (Journal American Chem-

ical Society, vol. 69, page 128; Journal American Chemical Society, vol. 71, page 3500) as applied to ephedrine, which consists essentially of acetylating the dextro and levo isomers of the erythro pair and hydrolyzing the acetylated product with dilute acid in order to bring about inversion. The penicillin G salts of the levo and dextro isomers forming the threo racemate of N-methyl-(2-hydroxy-1,2-diphenylethyl) amine are prepared by reacting an isomer of the base with free penicillin G in ethyl ether solution. The precipitated amorphous salts are isolated by decanting the ether and then drying. The dextro and levo isomers of the threo racemate of N-methyl-(2-hydroxy-1,2-diphenylethyl) amine in this specification are denominated d' and l' respectively. The penicillin G salt of the d' isomer has a specific rotation of $+192^{\circ} \pm 5^{\circ}$ in acetone at 25° C . taken within one-half hour after dilution while the specific rotation of the penicillin G salt of the l' isomer taken under the same conditions is $+155^{\circ} \pm 5^{\circ}$. The l' and d' isomers can be employed to form salts of other forms of penicillin just as described above for penicillin G.

Blood level tests were conducted wherein my new penicillin salts of N-methyl-(2-hydroxy-1,2-diphenylethyl) amine were given orally, and injected intramuscularly into dogs, the amount of penicillin in the blood stream being measured at definite intervals after administration. The following table shows the blood levels obtained after a portion of my new penicillin G salt of 1 - N - methyl - (2-hydroxy-1,2-diphenylethyl) - amine containing the indicated number of units of penicillin was injected intramuscularly as an aqueous suspension.

TABLE I

[Blood level; 120 mesh aqueous suspension—intramuscularly; units penicillin/ml. blood.]

Dog No.	Dose Units	Hours						
		0	6	12	24	36	48	60
79	60,000	0	.125	.096	.084			
31	60,000	0	.160	.092	.118

83	60,000	0	.390	.180	.101	.047	0	0
44	60,000	0	.170	.166	.102	.050	.051	0
62	60,000	0	.380	.340	.169	.049	0	0
39	60,000	0	.216	.102	.084	.051	.061	.042
41	60,000	0	.102	.071	.049	.031	.039	.037

The following table is offered for comparison purposes. It shows blood levels obtained when procaine penicillin G was injected intramuscularly, 60,000 units of penicillin being injected into each dog. Procaine penicillin G is accepted as being the best repository form of the antibiotic previously known.

TABLE II

[Blood levels; units penicillin/ml. blood; procaine penicillin—12 mesh aqueous suspension—intramuscularly.]

Dog No.	Dose Units	Hours					
		0	1	2	6	12	24
49	60,000	0	0.730	0.810	0.420	0.395	0
58	60,000	0	0.435	0.480	0.370	0.320	0
61	60,000	0	0.890	0.580	0.700	0.103	0
76	60,000	0	0.645	0.840	0.650	0.320	0

It can be seen from a comparison of Tables I and II giving data on blood levels obtained after intramuscular injections of the penicillin G salt of 1 - N - methyl - (2-hydroxy-1,2-diphenylethyl) amine and procaine penicillin G, that my new compound gives consistently longer blood levels than the previous most generally used repository form of penicillin.

The following table indicates blood levels obtained when my new penicillin G salt of 1-N-methyl-(2-hydroxy-1,2-diphenylethyl) amine was administered orally, 100,000 units of penicillin being administered to each dog.

TABLE III

[Blood levels; 100,000 unit tablet—orally; units penicillin/ml. blood.]

Dog No.	Hours				
	0	2	4	6	8
39	0	0.126	0.066	0	0
41	0	0.144	0.231	.057	0

The following table shows blood levels obtained when my new penicillin G salt of d-N-methyl-(2-hydroxy-1,2-diphenylethyl) amine was administered orally, 100,000 units of penicillin being administered to each dog.

TABLE IV

[Blood levels; 100,000 unit tablet—orally; units penicillin/ml. blood.]

5

The following table is a summary of clinical data obtained when my new penicillin G salt of 1-N-methyl-(2-hydroxy-1,2-diphenylethyl) amine was used therapeutically in man. In each case a single 300,000 unit dose of my new compound was injected intramuscularly and the blood level obtained in the usual manner.

TABLE VII

[Blood levels; 300,000 units; aqueous suspension—intramuscularly in man; units penicillin/ml. blood.]

Patient	Hours			
	6	24	48	72
1	0.125	0.125	0.06	0

16	0.25	0.06	0.06	0
17	0.25	0.125	0.06	0.03
18	0.25	0.125	0.06	0.06

The following table is also offered for comparison purposes. It shows blood levels obtained when procaine penicillin G was injected intramuscularly into man, 300,000 units of penicillin being administered to each patient.

TABLE VIII

[Blood levels; 300,000 units of procaine penicillin G aqueous suspension intramuscularly in man; units penicillin/ml. blood.]

Patient	Hours			
	6	24	48	72
1	1.0	0	0	0
2	1.0	0	0	0
3	1.0	0.03	0	0
4	2.0	0	0	0
5	0.5	0	0	0
6	0.5	0.125	0	0
7	0.125	0.06	0.03	0
8	0.5	0.125	0	0
9	0.5	0.03	0	0
10	1.0	0.125	0	0
11	0.5	0.125	0.03	0
12	0.5	0.03	0	0
13	1.0	0.125	0	0
14	0.5	0.03	0	0
15	0.5	0.06	0	0
16	0.25	0.125	0.03	0
17	0.5	0	0	0
18	0.25	0.03	0	0

It can be seen from a comparison of Tables VII and VIII that my new penicillin G salt of N - methyl-(2-hydroxy-1,2-diphenylethyl) amine gives consistently longer blood levels in man when injected intramuscularly than the form of the antibiotic currently considered most efficient.

In another series of tests twenty-three selected patients were treated with both procaine penicillin G and the penicillin G salt of 1-N-methyl-(2-hydroxy - 1,2 - diphenylethyl) amine. Of the twenty-three patients treated, twelve were hypersensitive to procaine penicillin G, while but one was sensitive to the penicillin G salt of 1-N-methyl-(2-hydroxy - 1,2 - diphenylethyl) amine, this patient developing an urticarial eruption. A further advantage in the use of my new penicillin salts is illustrated in the following case. Twenty-four hours after starting regular crystalline procaine penicillin G therapy for a pelvic

infection, the patient developed a severe urticarial rash and edema accompanied by slight elevation of temperature. The penicillin G salt of 1-N-methyl-(2-hydroxy-1,2-diphenylethyl) amine was immediately substituted and all signs of reaction cleared completely in 36 hours and did not return during the entire course of treatment with my new penicillin salt. Thus it is shown to be possible to give my new penicillin salt even in the face of known penicillin sensitivity.

The following table shows the results of toxicity tests of the new penicillin G salt of 1-N-methyl-(2 - hydroxy-1,2-diphenylethyl) amine conducted on laboratory mice. The table shows the amount of my new compound which can be administered without any mouse fatalities and the amount given to produce a 50% kill of the mice tested. The penicillin salt was injected intraperitoneally and subcutaneously as indicated in the table.

20

TABLE IX

Mouse toxicity

	LD ₀	LD ₅₀	mg./kg. of Body Weight of Test Mice	
			Intraperitoneally	Subcutaneously
30	50	180±27		LD ₄₀ =300

The minimal dose of the penicillin G salt of 1 - N - methyl-(2-hydroxy-1,2-diphenylethyl) - amine showing cutaneous irritation is greater than 200 mg. per kg. of body weight of the test mice but less than 400 mg. per kg. of body weight of the test mice. A single dose of 5,000,000 units of the penicillin G salt of 1-N-methyl-(2-hydroxy-1,2-diphenylethyl) amine in aqueous suspension was injected subcutaneously into two dogs and the dogs subsequently observed for a period of 48 hours. No toxic or irritative symptoms were observed during the 48 hours.

The following table shows the results of acute toxicity tests of the new penicillin G salt of d - N - methyl-(2-hydroxy-1,2-diphenylethyl) amine conducted on laboratory mice. The salt was given orally and injected intraperitoneally and subcutaneously as shown in the table.

50

TABLE X

Mouse toxicity

	LD ₀	LD ₅₀	mg./kg. of Body Weight of Test Mice	
			Intraperitoneally	Subcutaneously
60	300	418±42		
	2,000	2,420±262		
	2,500	3,150±215		

From a consideration of the above tables it can be seen that my new compounds are distinct improvements over procaine penicillin G which has been considered to be the best form of penicillin available to the trade.

My new compounds are therapeutically effective antibiotic compounds and are useful in treating diseases in man and animals caused by penicillin susceptible organisms.

This application is a continuation-in-part of my application Serial Number 164,029, filed May 24, 1950, now abandoned.

75

Now having disclosed my invention what I claim is:

1. The penicillin salts of N-methyl-(2-hydroxy-1,2-diphenylethyl) amine.
2. The penicillin G salts of N-methyl-(2-hydroxy-1,2-diphenylethyl) amine.
3. The penicillin G salt of dl-N-methyl-(2-hydroxy-1,2-diphenylethyl) amine.
4. The penicillin G salt of l-N-methyl-(2-hydroxy-1,2-diphenylethyl) amine.

10

5. The penicillin G salt of d-N-methyl-(2-hydroxy-1,2-diphenylethyl) amine.
6. The penicillin G salt of dl(threo)-N-methyl-(2-hydroxy-1,2-diphenylethyl) amine.
7. The penicillin G salt of l-(threo)-N-methyl-(2-hydroxy-1,2-diphenylethyl) amine.

VERNON V. YOUNG.
